UNITED STATES PATENT OFFICE.

ALLAN A. CAMERON, OF CHICAGO, ILLINOIS, ASSIGNOR TO OLIVER C. RITZ WOLLER, OF CHICAGO, ILLINOIS.

DESIGN FOR AN ORNAMENT FOR AUTOMOBILE RADIATOR CAP OR SIMILAR ARTICLE.

Application filed October 22, 1927. Serial No. 23,847. Term of patent 14 years.

To all whom it may concern:

Be it known that I, ALLAN A. CAMERON, a citizen of the United States, residing at Chicago, in the county of Cook and State of Illinois, have invented a new, original, and ornamental Design for an Ornament for Automobile Radiator Cap or Similar Article, of which the following is a specification, reference being had to the accompanying drawing, forming part thereof.

In the drawing,—

Fig. 1 is a side elevational view of an or-

nament for automobile radiator cap or similar article showing my new design, the ornament being shown as tilted slightly to bring the top closer than the base to the observer;

Fig. 2 is a perspective view of the ornament; and

Fig. 3 is a plan view of the ornament.

I claim:—

The ornamental design for an ornament for automobile radiator cap or similar article, substantially as shown.

ALLAN A. CAMERON.
